UNITED STATES PATENT OFFICE.

RUSSEL S. BARNUM, OF CHICAGO, ILLINOIS, ASSIGNOR TO HARRY C. GOODRICH, OF SAME PLACE.

ATTACHMENT-HOLDER FOR SEWING-MACHINES.

SPECIFICATION forming part of Letters Patent No. 397,887, dated February 19, 1889.

Application filed April 26, 1887. Serial No. 236,241. (No model.)

To all whom it may concern:

Be it known that I, RUSSEL S. BARNUM, residing at Chicago, in the county of Cook and State of Illinois, and a citizen of the 5 United States, have invented a new and useful Improvement in Detachable and Adjustable Sewing-Machine Attachments, of which the following is a specification, reference being had to the accompanying drawings, in 10 which—

Figure 1 is a top or plan view of the carrying-plate and the hemmer; Fig. 2, a top or plan view of the attaching-plate and adjusting-lever; Fig. 3, a top or plan view showing the 15 hemmer-plate in position to be locked by the lever; Fig. 4, a top or plan view showing the parts, together with the hemmer, adjusted in one position; Fig. 5, a top or plan view of the parts, together with the hemmer, adjusted in 20 another position; Fig. 6, a top or plan view showing a modification in the connection of the parts; Fig. 7, a detail showing a modification in the connections between the lever and the hemmer-plate; Fig. 8, a cross-section 25 showing the construction of the connection of Fig. 7.

The object of this invention is to furnish a detachable, and at the same time adjustable, attachment for sewing-machines by which one 30 attachment can be readily taken out and replaced by another, and at the same time have all the attachments readily and quickly adjustable for the line of stitching; and its nature consists in the several parts and combinations of parts hereinafter described, and 35 pointed out in the claims as new.

In the drawings, A represents a plate of the same dimensions as the ordinary plate for the shuttle-race, which plate can be substituted 40 for the shuttle-race plate when the attachment which it carries is to be used. As shown, this plate has a notch or recess, a, cut therein to facilitate its withdrawal.

B is an arm or lever attached by a suitable 45 pin or pivot, b, to the plate A, and having a hole, b', in it to receive the pin of the hemmer-plate, and, as shown in Figs. 1 to 6, this lever has an ear or projection, b'', which can be caught and serve as a means to throw the lever 50 up for disengagement from the hemmer-plate.

C is a hemmer-plate, having an ear, c, in the form of construction shown in Figs. 1, 3, 4, and 5, which ear can be inserted in the hole d in the plate A and form a connecting point and pivot for the hemmer-plate. As shown in 55 Fig. 6, the ear c is struck down at the center, so as to form a portion to enter the hole d, with an overlying portion to rest on the plate A when the parts are together. As shown in Fig. 7, the ear is dispensed with and a countersink is formed in the end of the plate, so as to leave an edge to enter the hole d; but the countersink serves the same purpose as the ear. 60

D is a hemmer formed with or suitably connected to the plate C. As shown in Figs. 1 to 65 5, inclusive, the plate C is provided with a pin, c', to enter the hole b' and lock the hemmer-plate to the lever B, and, as shown in Figs. 6 and 7, the pin c' enters a slot, f', in the lever B, which slot, as shown, is curved, so as 70 to act on the pin and move the hemmer-plate from the movement of the lever, and also to lock the lever to the hemmer-plate. As shown in Fig. 7, the pin c' is cone-shaped, and with this form of pin the connection between the 75 hemmer-plate and the lever is broken by simply taking hold of the hemmer end of the plate and withdrawing the plate from beneath the lever, dispensing with the lifting-lip b'', used in the other forms of construction. As shown 80 in Figs. 2, 3, 4, and 5, the lever B has a tooth, e, to engage with notches in an edge, e', on the plate A and lock the lever in any position in which it may be desired. As shown in Fig. 6, the lever B is held in any position in which 85 it may be placed by frictional contact, and the limit of movement in either direction of the lever is stopped by projections f on the plate A. The lever B, as shown, is struck up or recessed to adapt it to overlap the hemmer- 90 plate.

The parts are assembled by inserting the lip c into the hole d and turning the plate C so that it overlies the plate A, and then bringing the lever B over the plate C until the pin 95 c' can enter the hole b', which locks the hemmer-plate to the lever and maintains the plate in position, and at the same time the lever can be moved to bring the delivery end of the hemmer in proper relation with the needle to 100

have the stitching in proper relation with the edge. The attachment can be changed and another attachment substituted therefor by lifting the lever through the ear b'' until the 5 pin c' is disengaged from the hole or slot b , when the plate C can be removed and another plate with another form of attachment be slipped into place, with its tongue c in the hole d and its pin c' in engagement with the 10 hole b' . The attachment shown in Fig. 6 is secured in place and adjusted in substantially the same manner as already described. The ear c is dropped into the hole d and the pin c' engaged with slot b' , so that by moving the 15 lever B the delivery end of the hemmer can be adjusted for the line of stitching. The attachment of the parts, with the construction shown in Fig. 7, is the same as already described, except that owing to the tapering 20 form of the pin c' , it is not necessary to raise the lever in withdrawing one attachment and inserting another in place thereof. The ear or projection c forms the pivot in each case on which the hemmer is swung to adjust its 25 delivery end, and this swinging of the hemmer is from the throw of the lever B, and when adjusted the lever is locked in position through the tooth e and the notched edge e' , or otherwise. The necessary end movement 30 of the plate C to permit the side play of the hemmer for the adjustment in the arrangement shown in Figs. 1 to 5, inclusive, is provided for by the slipping of the ear c endwise

in the hole d , and such end movement for the arrangement shown in Figs. 6 and 7 is permitted by the slot f' , which allows the lever B to be swung to carry the hemmer D sidewise. 35

What I claim as new, and desire to secure by Letters Patent, is—

1. The combination of plate A, having hole 40 d , the plate C, provided with ear c , fitting in the hole d to render said plate C detachable and adjustable, the lever B, pivoted to plate A and struck up or recessed to overlap the plate C, means for connecting the lever B and 45 plate C, whereby said plate may be adjusted, and means for securing the lever B in the position to which it may be turned, substantially as described.

2. The combination of plate A, having hole 50 d and notched edge e' , the plate C, provided with ear c , fitting in the hole d , said plate being also provided with pin c' , and the lever B, pivoted to plate A and having an opening, 55 b' , to receive the pin c' , whereby said lever is connected with the plate C, said lever being struck up or recessed to be swung over upon and overlap the plate C, and provided with a tooth, e , to engage the notched edge e' of the plate A, whereby the lever is held in the position to which it may be turned, substantially 60 as described.

RUSSEL S. BARNUM.
